UNITED STATES PATENT OFFICE.

JOHN FRANCIS BOORAEM, OF NEW YORK, N. Y., AND BERNARD JACQUART,
OF SOUTH RIVER, NEW JERSEY.

DESIGN FOR A TILE.

SPECIFICATION forming part of Design No. 33,481, dated October 30, 1900.

Application filed October 4, 1900. Serial No. 32,063. Term of patent 14 years.

To all whom it may concern:

Be it known that we, JOHN FRANCIS BOORAEM, a resident of the borough of Manhattan, in the city and State of New York, and 5 BERNARD JACQUART, a resident of South River, in the county of Middlesex and State of New Jersey, citizens of the United States, have invented and produced a new Design for a Tile, of which the following is a specification.

The essential feature of our design consists in a tile which is substantially square in form when viewed from the top and bottom, which is of vertically-elongated rectangular form 15 when viewed from the front and back, and which is of irregular polygonal form when viewed from either side, bounded as follows: A diagonal line connecting the vertical front line with the horizontal top line and two inwardly-extended converging lines connected 20 with each other and connecting the horizontal bottom line with the vertical back line, thus forming a reentrant angle in the back of the tile.

25 In the accompanying drawings, Figure 1 is a view of the tile in top plan. Fig. 2 is a front view of the same. Fig. 3 is a side view of the tile. Fig. 4 is a back view, and Fig. 5 is a bottom plan view, of the tile.

The tile is denoted as a whole by A, and it is of such form that it presents a substantially square figure when viewed from the top and bottom and a vertical elongated rectangular figure when viewed from the front and back.

35 The front of the tile is cut away, as shown at a, and the rear of the tile is cut away, as shown at a', to form a reentrant angle in the tile, so that when the tile is viewed from either side it presents an irregular figure having a diagonal line connecting the front vertical line of the tile with the horizontal top line and two inwardly-extended converging lines connected with each other at their inner ends and connecting the horizontal bottom line 40 with the vertical back line.

45 What we claim is—

The design for a tile substantially as herein shown and described.

In testimony that we claim the foregoing as 50 our invention we have signed our names, in presence of two witnesses, this 21st day of September, 1900.

JOHN FRANCIS BOORAEM.
BERNARD JACQUART.
